J. E. DUNN.
MECHANISM FOR CONCENTRATING LIQUIDS.
APPLICATION FILED NOV. 8, 1911.

1,038,559.

Patented July 23, 1912.

FIG. 1.

UNITED STATES PATENT OFFICE.

JOSEPH E. DUNN, OF PHILADELPHIA, PENNSYLVANIA.

MECHANISM FOR CONCENTRATING LIQUIDS.

1,033,559.

Specification of Letters Patent.

Patented July 23, 1912.

Application filed November 6, 1911. Serial No. 658,803.

To all whom it may concern:

Be it known that I, JOSEPH E. DUNN, a British subject, residing in the city of Philadelphia, county of Philadelphia, and 5 State of Pennsylvania, have invented an Improved Mechanism for Concentrating Liquids, of which the following is a specification.

This invention relates to the evaporation 10 and concentration of sugar and other solutions by heating tubes extending therethrough and it contemplates heating the solution by subjecting it in bulk to direct contact with vertical tubes having lower open 15 ends in communication with a steam chamber and upper ends, closed excepting vents, terminating in the evaporating chamber above the level at which the solution is maintained automatically.

20 In the drawings, Figure 1 is an elevation, part sectional, of apparatus embodying my invention; Fig. 2 is a vertical sectional view of a modified apparatus; Fig. 3 is an enlarged view, part sectional, of the upper 25 part of a tube shown in Fig. 1; and Fig. 4 is an enlarged view, part sectional, of the upper part of a tube and connections shown in Fig. 2.

As shown in Fig. 1 of the drawings, the 30 shells 1 and 1' have therein the respective sheets 2 and 2' forming, respectively, in the shell 1, the top evaporating chamber 3 and the bottom steam chamber 4, and, in the shell 1', the top evaporating chamber 3' and the bottom steam chamber 4'. Heating tubes 5 and 5' have their lower open ends set in the respective sheets 2 and 2' so as to communicate with the respective steam chambers 4 and 4', and their upper ends, 40 which extend into the respective evaporating chambers 3 and 3' to points above the liquid levels thereof, substantially closed by caps 5^a, the latter having vents 5^b therein through which air, collecting in the tops of the tubes, 45 escapes, as illustrated in Fig. 3.

Liquor is supplied to the chamber 3 through a conduit 6 under control of mechanism comprising a box 7 connected therewith, a valve 8 for controlling the flow 50 through the box, a fulcrumed lever 9 for operating the valve and a float 10 for operating the lever so that when such liquor has risen to the desired level in the chamber 3 the float will be elevated and the valve 8 closed. A pipe 11 connects the vapor space 55 of the chamber 3 with the top of the box 7.

to permit the escape of air therefrom. Liquor, partly concentrated, flows from the chamber 3 to the chamber 3' through the conduit 6' containing the box 7' which has 60 therein the valve 8', lever 9' and float 10', whereby the flow of liquor is cut off by the rise of the float 10' and the closure of the valve 8' when the desired level is reached. Liquor, partially or finally concentrated, is 65 withdrawn from the chamber 3' by the conduit 6'' provided with the valves 6^a and 6^b. A branch conduit 6''', containing the box 7'', is connected with the conduit 6'' on opposite sides of the valve 6^b, the box being 70 connected by the equalizing conduit 7^a with the chamber 3' at the liquor level thereof. A valve 8'', a fulcrumed lever 9'' and a float 10'', in the box 7'', control the discharge through the duct 6''', the float being 75 of such weight that it will rise and open the valve when the liquor attains the desired density. The density of liquor at which this valve opens can be regulated by a lever 12, pivotally connected to the box 7'' and to the valve stem 8^a, and a weight 12^a adjustable on the lever.

It will be understood that during the process of evaporation the valve 6^a is open and the valve 6^b closed and that when the 85 desired density has been reached the valve 6^b can be opened to facilitate the discharge.

Steam is introduced to the chamber 4 by the conduit 4^a and rises in the tubes 5 which are heated thereby and heat the liquor circulating in bulk in contact therewith and baffled thereby. Air (which is permitted to escape from the tops of these tubes through the vents 5^b so that steam may act upon the full tube lengths) and vapor (which rises 90 from the heated liquor) are discharged from the top of the chamber 3 through the conduit 13 to the chamber 4'. The tubes 5', communicating with the chamber 4', are heated by this vapor and heat the partially concentrated liquor circulating in bulk in contact therewith and baffled thereby. The air discharged through the vents in the tops of these tubes and the vapor rising from the liquor in process of treatment are discharged 95 from the top of the chamber 3' by the conduit 14.

The construction illustrated in Fig. 2 comprises the shell 1 having therein the tube sheet 2 forming the vapor chamber 3 and the heating chamber 4 and in the chamber 3 the vertical tubes 5 having their lower ends 110

set in the sheet 2 so as to communicate with the chamber 4, as illustrated in Fig. 1. But these tubes have their substantially closed tops connected with a pipe or conduit 15 by 5 nipples 16, as more clearly shown in Fig. 4, whereby air can be drawn off from the tops of the tubes, through the side of the shell, while no substantial amount of steam can escape owing to the small bore of such 10 nipples.

It will be understood that owing to the lower pressure in the evaporating chambers a degree of suction will act through the tube vents where such vents are in direct communication with such chambers to withdraw air from the tops of the tubes and where such vents communicate with a discharge pipe suction can be communicated through such pipe in any desired manner.

20 By the foregoing mode of operation substantially the total energy of the steam is communicated through the tubes to the liquor. Substantially the total tube surface is in contact with the liquor and active. The 25 liquor can be brought to any desired degree of density and automatically discharged, whether in the final form or concentrated to the degree desired for further treatment.

Having described my invention, I claim:
30 1. The mechanism for evaporating solutions which comprises a shell containing a sheet dividing it into a heating and an evaporating compartment, substantially vertical tubes in said evaporating compartment having their tops closed excepting air vents and

their open bottoms set in said sheet in communication with said heating compartment, and means for introducing liquid into said evaporating compartment and preventing the same from rising to the level of the air 40 vents in said tubes.

2. The mechanism for evaporating solutions which comprises a shell having therein a sheet dividing it into an evaporating and a heating compartment, substantially vertical tubes in said evaporating compartment having their upper ends closed excepting air vents and their lower open ends set in said sheet in communication with said heating compartment, means for discharging air 45 from said tubes, and means for withdrawing air discharged from said vents and vapor rising from the solution in said evaporating chamber.

3. The mechanism for evaporating solutions which comprises a shell having therein a sheet dividing it into an evaporating and a heating compartment, substantially vertical tubes in said evaporating compartment having their lower open ends set in said 60 sheet in communication with said heating compartment, and means for withdrawing gases through the tops of said tubes.

In witness whereof I have hereunto set my name this 3rd day of November, 1911, in 65 the presence of the subscribing witnesses.

JOSEPH E. DUNN.
